United States Patent Office

Des. 193,119
Patented June 26, 1962

193,119

COMPARTMENTED CONTAINER

John Donald Bostrom, Niles, Ill., assignor to Poster Packaging, Inc., Chicago, Ill., a corporation of Delaware

Filed Mar. 8, 1961, Ser. No. 64,185

Term of patent 14 years

(Cl. D58—13)

FIG. 4

FIG. 2

FIG. 3

I claim:

The ornamental design for a compartmented container, as shown.
